VARIABLE STROKE MECHANISM

Albert J. Harris, Chicago, Ill., assignor to Hills-McCanna Company, Chicago, Ill., a corporation of Illinois

Application October 26, 1934, Serial No. 750,057

2 Claims. (Cl. 74—40)

My invention relates to pumps and particularly to chemical pumps having capacity adjustment to permit supplying different proportionate amounts of liquid chemicals.

5 The invention relates in some aspects to liquid pumps covered by Patents Numbers 1,858,184 and 1,858,185, issued May 10, 1932, to C. O. Buenger of Chicago, Illinois.

One of the objects of the present invention is 10 to provide a simple, practical and advantageous construction of pump of the class specified.

Another object of the invention is to provide improved and advantageous means for securing adjustment of the capacity of the pump.

15 Another object of the invention is to secure this adjustment without unfavorably affecting the stroke of the piston.

Other objects of the invention will appear and be pointed out hereinafter.

20 In the accompanying drawings:

Fig. 1 is a side elevation of a pump embodying my present invention;

Fig. 2 is a plan view of the same;

Fig. 3 is a vertical elevation taken on the line

25 3—3 in Fig. 1;

Fig. 4 is a horizontal section taken on the line 4—4 in Fig. 1;

Fig. 5 is a vertical-section of the lower end of the pump cylinder; and

30 Fig. 6 is a transverse section taken on the line 6—6 in Fig. 5.

In the accompanying drawings, I show a pump embodying a base 1 on which may be mounted an electric motor 2 connected by a rotary shaft 3 to a speed reducing device 4.

35 The speed reducing device 4 is preferably provided with a rotary crank arm 5 whose outer end is pivotally connected at 5^a to one end of a link 6, the other end of link 6 being pivotally connected at 7 to a swinging yoke 8 which is pivotally connected at its opposite end by pivots 9 to swinging arms 10 which are in turn pivotally connected at 11 to the upper end of the pump case 12, which latter is secured by bolts 14 to a base 15 40 on the main base or platform 1.

The yoke 8 is pivotally connected with the reciprocating piston or plunger 16 which is arranged to reciprocate in the piston cylinder or barrel 17 on the case 12, being preferably formed 45 integrally and as a part of said case 12. The rotation of crank arm 5, resulting in the actuation of link 6 and swinging of yoke 8 about its fulcrum pivots 9, results in the reciprocation of plunger 16 and thereby effects the pumping act.

50 This yoke 8 is preferably arranged for longi-

tudinal adjustment so that its point of pivotal connection with piston 16 may be varied, thereby changing its stroke and thereby causing a variation in the length of the piston stroke to accomplish the desired variation in the amount of liquid pumped to secure desired proportions in a chemical mixture or the like. This longitudinal shifting of the yoke 8 and consequent change of point of pivotal connection of said yoke with reciprocating plunger 16, has certain definite advantages which will be pointed out later on.

55 While the longitudinal shifting of this yoke 8 and consequent variation in the point of pivotal connection with the reciprocating plunger could be accomplished in various ways, I show herein one construction which I have found very advantageous and satisfactory.

20 In this construction the yoke 8 is preferably formed of two side members 8^a—8^a, which are arranged on opposite sides of the pump plunger 16, and these side members 8^a are made in the form of guides to support and guide a carriage 18 which is preferably made in U form, as shown in Fig. 4, and fitted between the side members 8^a—8^a and provided with longitudinal side 25 slots to receive said side members 8^a, as shown in Fig. 3, whereby the yoke 8 may be shifted along carriage 18 by sliding on the members 8^a. The sides of the carriage 18 are arranged on opposite sides of piston 16, as shown in Fig. 4, and provided with screws 19 which serve as pivotal pins for pivotally connecting carriage 18 with piston 16. For shifting yoke 8, a rotary member 21 is provided and arranged for rotation in a bearing 22 30 in carriage 18 but will be held against longitudinal movement by ring 23 fitting in a recess in the end of rod 21 and in a co-operating recess in carriage 18.

35 This rod 21 extends lengthwise of yoke 8 and out through an end member 24 thereon, being provided with a handwheel 25 at its outer end. Said rod 21 is screw-threaded and co-operates with the threads on cross-member 24, as shown in Fig. 4, whereby rotation of handwheel 25 will cause rotation of rod 21 and adjustment of said 40 rod relatively to yoke 8 by means of threads on said rod 21 and member 24, and thereby cause the shifting of yoke 8 longitudinally along yoke bars 8^a and the consequent change in the point of pivotal connection of yoke 8 with the piston 45 rod or plunger 16.

50 Thus it will be seen that this longitudinal adjustment of yoke 8, with its effect of changing the point of pivotal connection between said yoke and reciprocating plunger 16, has the effect of 55

changing the point of application of power of the lever which is in effect formed by yoke 8, and shortening or lengthening the length of lever arm or part of the lever which acts upon plunger 16 and thereby varies the length of stroke of said plunger 16. As handwheel 25 is turned to shift yoke 8 to the right, (Fig. 1) the distance between pivots 19 and 9 is decreased, and consequently the effective length of lever 10 formed by yoke 8 is shortened and the plunger 16 will have a shorter stroke. Likewise, a converse shifting of yoke 8 to the left, (Fig. 1) will have the effect of increasing the distance between pivot pins 9 and 19, thereby lengthening 15 the effective lever arm operating on the piston 16 and lengthening the stroke of said piston.

A marked advantage of this arrangement is that while the stroke of the piston is thus varied as desired to secure changes in the piston stroke 20 and consequent changes in the pump output, the stroke or location of the piston or plunger is not unfavorably affected, as has been the case in other constructions for securing variation in the plunger stroke. This is due to the fact that shifting 25 of yoke 8 to one side or the other retains the point of pivotal connection between yoke 8 and plunger 16 at substantially the same height or elevation and so does not have the effect of varying the position of the piston, in the cylinder, 30 by bodily raising or lowering it and causing it to work in a different position in the piston chamber, as is the case with certain other constructions and arrangements for securing variation of piston travel. This present arrangement on 35 the other hand has the effect of maintaining the piston plunger in a substantially constant position, changing only the length of stroke, notwithstanding shifting in the point of connection of piston with the yoke 8, and hence the piston will 40 work in the lower portion of the piston cylinder where it is originally placed by adjustment of the parts, notwithstanding changes in the length of stroke of the piston.

Referring to Figs. 5 and 6, there is shown in 45 those figures an arrangement for packing and cleansing the piston in the piston cylinder, so as to prevent the formation of solid material from the chemical solutions which would interfere with the proper operation of the pump.

These figures show the piston rod 16 with its 50 lower enlarged end 16^a and the upper end of the piston cylinder or chamber 17, and a stuffing box arrangement for the same. This stuffing box arrangement involves a packing gland 27 adapted 55 to fit in the upper end of cylinder 17, and packing material 28—28 arranged in the packing chamber, and a ring 29 also arranged in said chamber and surrounding the piston end 16^a and

dividing the packing material 28 into two parts. This ring 29 has apertures 30 which are arranged opposite apertures 31 formed in the cylinder end 17, so that an inlet pipe for the liquid may be connected to one aperture 31 and an outlet pipe 5 for the same to the other aperture 31, thereby permitting circulation of water or other liquid, if desired, through the packing gland to prevent freezing or coagulation of the chemical mixture being pumped, and for other purposes if desired. 10

It will be understood that changes and modifications may be made without departing from the spirit of the invention.

What I claim is:

1. Actuating means for a pump piston, comprising a power member having a rotary crank arm, a link having one end pivotally connected with said crank arm, a piston-actuating lever pivotally connected with the other end of said link, said piston-actuating lever being in the 20 form of a yoke extending crosswise of the piston and having members on opposite sides of the piston, a carriage along which the side members of said yoke are slidable and provided with pivot pins forming a pivotal connection with the piston, swinging supporting links pivoted at one end to the end of said yoke opposite said link and pivoted at the other end to the piston casting, and means for adjusting said piston connecting carriage lengthwise of said yoke, said 30 means comprising a rotary threaded bar or rod having one end connected with said carriage so as to permit rotary but prevent longitudinal movement, said threaded bar engaging a threaded member on the yoke, and a rotary handle on 35 said bar rod to turn the same and thereby cause said threaded bar rod to adjust said carriage.

2. Actuating means for a piston comprising a power member having a rotary crank arm, a link having one end pivotally connected to said crank 40 arm, a piston-actuating lever pivotally connected with the other end of said link, said piston-actuating lever comprising a pair of spaced parallel bars forming a pair of tracks, a U-shaped carriage embracing and pivotally connected to the piston and embraced by said bars and engaging said tracks, means for advancing said lever with respect to said carriage comprising a screw member engaging the bight portion of the U-shaped carriage and rotatable but immovable longitudinally with respect thereto, a transverse bar joining the two parallel bars, said screw being threaded through said transverse bar so that upon turning of the screw the parallel bars are moved with respect to the carriage, and a swinging fulcrum 50 for the piston-actuating lever.

ALBERT J. HARRIS.
